UNITED STATES PATENT OFFICE.

GEORGE G. THOMPSON, OF NEW YORK, N. Y., ASSIGNOR TO WISNER MANUFACTURING COMPANY, OF NEW YORK, N. Y., A CORPORATION OF NEW YORK.

CAN-COVER STERILIZER.

Application filed March 22, 1921. Serial No. 454,462.

To all whom it may concern:

Be it known that I, GEORGE G. THOMPSON, a citizen of the United States, residing in New York city, in the county of New York and State of New York, have invented certain new and useful Improvements in Can-Cover Sterilizers, of which the following is a specification.

My present invention relates to can cover sterilizers, for use more particularly for cleansing and sterilizing milk can covers, and one object is to provide a sterilizer of this kind which is efficient, simple in construction and cheap to manufacture.

In the present embodiment of my invention, the can covers are supported on their edge in a vertical position on an inclined bottom of the sterilizer, and move automatically by gravity along this bottom from one end of the sterilizer to the other, such movement preferably being a rolling movement of the can covers during which the surface of the inner portions of the covers, which it is particularly necessary to sterilize, are thoroughly, completely and continuously subjected to steam impinged against said inner surface portions, the cloud of expanding steam enveloping the outer surface portions of the covers.

In the accompanying drawings which show one embodiment of my invention and which form part of this specification, Figure 1 is a side elevation partly broken away.

Figure 2 is a plan view.

Figure 3 is a sectional view on the line 3—3, of Figure 1, on a larger scale than Figure 1.

Figure 4 is a sectional view on the line 4—4 of Figure 1, on the same scale as Figure 3.

Figure 5 is a fragmentary longitudinal sectional view, on the same scale as Figure 3.

Similar letters or numerals refer to similar parts throughout the several views.

My can cover sterilizer comprises a tank A, open at the top, and of suitable metal or material, and supported at a desired height as by the legs B.

The tank A, which preferably is of the rectangular shape shown, is provided with a downwardly inclined bottom 10, having therein at the deepest end of the tank an outlet 11, which can be closed or opened by any well known means, not shown. In the same end of the tank as the outlet 11, an

overflow outlet 12 is arranged to prevent the liquid level of the tank rising above a predetermined point, such as the line E—E.

A rod 13 extends from one end of the tank to the other, being supported in the ends of the tank and arranged at the same incline as the bottom 10, and longitudinal strips 14 and 15 are provided at the sides of the tank and also arranged at the same incline as the bottom 10, the purpose of the rod 13 and strips 14 and 15 being to afford means for guiding the can covers in rolling movement.

The bottom 10 is provided with parallel gutters 16 and 17, extending longitudinally for substantially the length of the bottom, these gutters having the same downward incline as the bottom 10 and preferably, for convenience, and cheapness of manufacture, being angle pieces resting upon the bottom 10 at the apex of the angle and secured to the bottom 10 as by the braces or brackets 18.

The steam pipe 19 extends longitudinally of the tank A, being supported in the ends thereof and provided with suitable valve means, not shown, for introducing steam thereinto and shutting off the steam therefrom. The steam pipe 19 is arranged in the tank A at an incline corresponding to the incline of the bottom 10 of the tank. The steam pipe 19 is provided for its entire length with perforations 20, Figs. 4 and 5, preferably located above the horizontal diameter of the pipe, and so arranged as to

cause jets of steam to be projected outwardly and upwardly from the pipe and to impinge against the inner surface portions, as the stoppers and inner faces of the caps, of the can covers as they move along in the tank from one end to the other thereof, whereby the inner surface portions of the can covers are thoroughly and continuously subjected to the steam jets, and the outer surface portions of the can covers are enveloped by the steam, the can covers preferably being supported in pairs in opposed relation open face to open face and in parallel vertical planes as shown in Fig. 3.

In operation steam is turned into the pipe 19. The can covers are manually placed in the tank at the shallower end thereof on opposite sides of the guide rod 13, preferably in pairs as shown in Fig. 3, the lower edges of the can covers resting in the gutters 16 and 17 as the case may be, and the upper

interior surface portions, in the present instance the stoppers, of the covers resting against the guide rod 13 and the respective strips 14 and 15. The can covers are then 5 allowed to roll by gravity along in the gutters 16 or 17 in a continuing series, being guided by the rod 13 and strips 14 and 15, and guided to an extent by the steam pipe 19, the inner surface portions being subjected 10 during this rolling movement to jets of steam from the perforations 20 of the steam pipe, and the outer surface portions of the can covers enveloped by steam, the can covers being manually removed from the 15 tank at the opposite end thereof in cleansed and sterilized condition.

In view of the foregoing it is to be noted that my apparatus is shown as being provided with means for maintaining water at 20 a stated level within the tank A, and is also provided with means 11, as previously noted, for draining the tank of such water when so desired.

In one form of use of my device, the sterilizing 25 of the can covers may be effected by causing the water to become of sufficient temperature through the introduction of steam, as previously noted, whereby the cans will be sterilized by either one or both 30 of the following actions:

First, the action of the steam impinging against the can covers thereby carrying water thereto wherein through the use of 35 said fluids every part of the interior of the cover is reached by a scouring action, thereby sterilizing fully and completely; and, second, by merely admitting sufficient steam to the bath to keep it a sufficient temperature to cause the desired sterilization. Mainly, 40 the idea of my device is that through the use of a tank, without any special moving mechanism therein, can covers may be caused to pass therethrough by gravity and while in the act of passing from one end of 45 the tank to the other caused to be treated by a sterilizing medium, preferably of hot water and steam either combined or sepa-

rate. It is also within the scope of my invention to cause these can covers to roll through any other suitable form of sterilizing medium. 50

Having thus described my invention, it should be understood that there may be modifications thereof and variations therein without departing from the spirit of the 55 invention, or exceeding the scope of the appended claim.

What I claim and desire to protect by Letters Patent is:

In a sterilizing device for milk can covers, the combination with a tank having a downwardly inclined base, of a plurality of angular guideways extending along the length of the base and parallel to one another, said guideways being adapted for receiving a plurality of can covers simultaneously, a fluid pipe disposed between and above said guideways, said pipe being positioned parallel to the base and adjacent to the lowest path of movement of the 70 rims of the can covers, a plurality of openings along the length of said pipe, said openings being formed in the upper segments on each side of the pipe whereby to form a plurality of angularly and upwardly distributed liquid sprays, a guide rod positioned above and parallel to said pipe, and co-operating with the guideways below and on each side thereof for maintaining the covers on their edges in a vertical position and for preventing the plurality of covers, one on each side of the fluid pipe from being displaced inwardly and contacting with one another, and bracket means on each side of and adjacent the 75 guide rod and co-operating with said guide rod for maintaining the can covers in vertical alinement throughout their passage along the guideways. 80
